UNITED STATES PATENT OFFICE.

VICTOR SUSSIN, OF CHICAGO, ILLINOIS, ASSIGNOR TO STEWART-WARNER SPEEDOMETER CORPORATION, OF CHICAGO, ILLINOIS, A CORPORATION OF VIRGINIA.

AUTOMOBILE BUMPER.

Application filed July 6, 1926. Serial No. 120,659.

The purpose of this invention is to provide an improved construction of bumper for automobiles. It consists in the elements and features of construction shown and described, as indicated by the claims.

In the drawings:

Figure 1 is a front perspective view of a bumper embodying this invention.

Figure 2 is a top plan view of the same.

Figure 3 is a direct front elevation.

Figure 4 is a detail section taken as indicated at line 4—4, on Figure 3.

Figure 5 is a detail section taken as indicated at line 5—5, on Figure 3.

Figure 6 is a detail section taken as indicated at line 6—6, on Figure 2.

Figure 7 is a fragmental detail plan view partly in section showing the relation of the ornamental finish plates to the impact bars and clamps.

The drawings show a bumper having its impact member composed of two bars, 1, 1, set edgewise, one directly above the other and spaced apart by a short vertical distance. Each of said impact bars has its opposite end portions, 2, reflexed forwardly and inwardly and lapped upon the body of the bar at a substantial distance from the middle point of its length and also at a substantial distance from the bend at 2^a, of the loop formed by such reflexing of the end portion, 2. The lapped ends of both bars at each side of the impact member are secured in lapped position by clamps, 3, 3, which extend vertically across both impact bars and have top and bottom flanges, 4, which are hooked over the upper and lower edges of the bars respectively. A single clamping bolt, 5, extends through each of the clamps, 3, and may be fitted with spacing washers, 6, for holding the lapped end portions, 2, 2, in proper vertical relation. The rear plate, 7, of the clamp device has in-turned spacing lugs, 8, which engage between the upper and lower bars, 1, 1, to hold them apart at the proper distance. A spring washer 9, and nut, 10, complete the clamp assembly.

For mounting the bumper on a vehicle, I provide a single bar, 11, which may be of stock similar to that used for the impact members, 1, 1, and which has a middle portion which is arched forward at 12, for attachment to the middle portion of the impact members by means of a central clamp,

13, which may be in the form of an ornamental shield or name plate, and serves principally to steady the middle portion of the impact member against excessive vibration and prevent it from rattling against the arched mounting bar at 12. The forward curving of the mounting bar provides space for the use of a starting crank when the bumper is mounted at the forward end of an automobile.

At the ends of the arched portion, 12, the mounting member extends laterally in opposite directions, these laterally extending portions, 14, being substantially aligned with each other and in the same vertical plane. They are provided with one or more apertures, 15, to receive attaching bolts, 16, by which the bumper may be secured to any suitable form of bracket on the vehicle frame, not shown. Laterally beyond the straight portions, 14, the mounting bar includes forwardly extending portions, 17, which diverge somewhat from each other and terminate in perforated end portions, 18, which are bent substantially at right angles to the parts, 17, to fit against the rear faces of the impact bars, 1, 1, at points laterally beyond the clamps, 3, 3. The extreme ends of the mounting member are reduced in width at 19, and bent to fit between the upper and lower impact bars, 1, 1, to serve as spacers at this point. The space between the impact members is considerably less than the width of the mounting bar, 11, so that a substantial portion of the latter overlaps at the rear face of each of the impact bars, 1, 1, while a clamping plate, 20, is lapped over the forward faces of the bars and held by a clamping bolt, 21, as clearly indicated in Figure 6.

The purpose of this construction is, first, to form the impact members with smoothly rounded ends which shall be somewhat flexible so as to slip clear of any obstruction which may be encountered by them in movement of the vehicle either forward or backward; and, second, to provide an impact surface by means of the flexed end portions, 2, which shall not be directly attached to the supporting bar, 11, and which, therefore, may flex or yield slightly before transmitting the force of impact to the mounting member. Thus these reflexed end portions, 2, will serve to cushion slight shocks such as those experienced in backing or parking a

car in closely crowded traffic, without even imparting such shocks to the bumper supports.

For the sake of ornamental appearance it may be desirable to finish the inwardly lapping end portions, 2, of the impact members in a manner or in a color which will provide a sharp contrast with the middle portion of the impact member exposed between the lapped ends. A preferred method of securing this effect is to paint or enamel the impact members in a dark color so that the end portions, 2, will be dark, and then to cover the middle portions with ornamental nickeled plates or strips, 22, which are preferably formed with upper and lower flanges, 23, engaging around the edges of the bars, 1, so as to practically conceal the impact bars themselves throughout the middle portion 20 of the bumper. It is much more economical to plate and polish these thin finish plates, 22, than to apply such a finish to the heavier impact bars, 1, and of course the addition of the ornamental plates in no way impairs the efficiency of the bumper for its primary purpose. The plates, 22, are firmly held in position by the grip of clamps, 3, holding them firmly under the overlapped ends, 2, of the impact bars, the ornamental strips, 22, being 25 cut of such a length as to extend slightly beyond the clamps, 3, as indicated in dotted lines in Figure 3, and as also seen in plan in Figure 7. This arrangement results in a 30 very handsome bumper which is an ornament as well as protection to the vehicle.

I claim:

1. In a bumper for motor vehicles, an impact member comprising a flat spring bar mounted edgewise vertically and having its opposite end portions looped by being flexed outwardly and then toward each other, and lapped against the impact side of the bar; a finish plate lapped upon the middle portion of said bar at said impact side and engaged 40 between the lapped ends of the loops and the body of the bar, together with clamping means applied at the lap of the loop ends for closing said loops and holding the finish plate in position.
2. A bumper for motor vehicles comprising a flat spring impact bar mounted edgewise vertically and having its opposite end portions looped by being flexed forwardly and inwardly and lapped against the forward surface of the bar, clamps applied over 45 the lap of the loop ends for closing said loops, and spring bar supporting means attached to the rear portions of the end loops intermediate their extreme outer portions and the said clamps.

3. A bumper for motor vehicles comprising a flat spring impact bar mounted edgewise vertically and having its opposite end portions looped by being flexed forwardly and inwardly and lapped against the forward surface of the bar, clamps applied over the lap of the loop ends for closing the loops and a mounting bar having a middle portion arched forwardly for connection to the impact member at its middle and having end 65 portions attached to the rear parts of the respective end loops of the impact member laterally beyond the aforesaid clamps.

4. A bumper for motor vehicles comprising a plurality of flat spring impact bars 75 mounted edgewise vertically, one above the other, and spaced apart vertically, each bar having its opposite end portions looped by being flexed forwardly and inwardly and lapped against the forward surface of the 80 bar; clamps applied across the spaced bars at the lap of the loop ends thereon for securing the bars rigidly together in spaced relation, and closing the loops, together with a mounting bar having a middle portion 85 arched forwardly and connected to the impact member at the middle of its width, and end portions attached to the rear parts of the respective end loops of the impact member intermediate their extreme outer ends 90 and the said clamps.

5. In the combination defined in claim 4, said mounting bar having portions intermediate its ends and the arched middle portion, which are flexed rearwardly and include perforated sections extending transversely of the vehicle to receive securing bolts 95 for attaching the bumper to the vehicle frame.

6. In a bumper for motor vehicles, an impact member comprising a flat spring bar mounted edgewise vertically and having its opposite end portions looped by being flexed forwardly and inwardly and lapped against the forward surface of the bar; a finish plate 100 lapped upon the middle portion of said bar at its forward side and engaged between the lapped ends of the loops and the body of the bar, clamps applied at the lap of the loop 105 ends for closing said loop and holding the finish plate in position, said plate having a marginal flange fitting over the edge of the impact bar, and the clamps having bent end portions engaging said edge of the bar, the flange of the plate terminating adjacent said end portions of the clamps abutting them to space said clamps laterally on the bar, the face of the plate extending beyond its flanges 110 for securement under the loop ends.

VICTOR SUSSIN.
